ABSTRACT

A permissible blasting machine employs a capacitive discharge circuit for electrically detonating an explosion in a hazardous environment. Protective circuitry prevents capacitor discharge until full charge is reached. After detonation, redundant circuitry dissipates any charge remaining in the circuit. A failure of the dissipating circuitry disables the discharge system.

FIG. 3

PRIMARY AND SECONDARY SHUNT PATHS FOR DISSIPATING AN ELECTRICAL CHARGE

BACKGROUND OF THE INVENTION

In underground mines an electrical charge is commonly used to detonate explosives. After a detonator ignites, a short time, which is a function of the delay period of the detonator, lapses before the explosion occurs. To prevent secondary explosions of gases and fine combustible particles, it is necessary to effectively quench the electrical charge within this short lapse between ignition and explosion. U.S. Bureau of Mines Schedule 16E requires that the voltage across the terminals of an electrical blasting machine be reduced to a level precluding accidental post firing ignition within 15 milliseconds after initial detonating contact is made. A device operating within the 15 millisecond limitation is classified as a permissible blasting machine.

Because of extreme hazards incident to underground blasting, operating safety is a primary consideration in the design and use of permissible blasting machines. Close scrutiny of new designs by the Bureau of Mines safeguards operators of permissible machines in proper working order operating within design limitations. Yet, hard use under unfavorable conditions often deteriorates the machines, resulting in unsafe operation. With prior permissible blasting machines there is no assurance that the charge quenching circuitry is functioning properly, and no indication of potentially unsafe operation. To overcome this defect of the prior art, this invention was made.

SUMMARY OF THE INVENTION

Our invention is a permissible blasting machine for safely detonating explosions in hazardous atmospheres. To provide the necessary electrical current for igniting a series circuit of up to 50 detonators, each having 16-foot long iron or copper legwires, a capacitive discharge circuit is used. Shortly after ignition, a primary shunt circuit provides a path for dissipating any voltage on the firing line or across the detonators within the required 15 millisecond period. As a backup, a second shunt circuit activates shortly afterward, again within the 15 millisecond period. If sufficient current passes through the secondary shunt due to a defect in the primary shunt, the entire blasting machine is automatically disabled.

One potential hazard in operating a blasting machine is the possibility of detonating only a fraction of the total number of detonators employed. With the high number of detonators our machine is capable of detonating, this possibility becomes extremely undesirable. A common cause of failure to initiate all detonators is the discharge of the energy storage capacitors before full charge is reached. To preclude this possibility, our invention employs a lockout circuit which prevents firing of the blasting machine until the capacitors are fully charged. These and other features of our invention result in a safe and efficient machine for underground blasting.

Therefore, one object of our invention is a blasting machine with redundant shunt circuits for removing a voltage from a load within a predictable period.

Another object of our invention is a blasting machine which is automatically disabled if an operating defect occurs.

Another object of our invention is a blasting machine in which firing is prevented until sufficient charge for complete detonation is available.

These and other objects of our invention are evident in this specification and drawing.

BRIEF DESCRIPTION OF THE DRAWING

FIG. 1 is a schematic detonation circuit of a blasting machine.

FIG. 2 is a schematic timing circuit of a blasting machine.

FIG. 3 is a schematic SCR drive circuit of a blasting machine.

DESCRIPTION OF THE PREFERRED EMBODIMENT

The detonating circuit 10 of a permissible blasting machine is shown in FIG. 1. To energize a series of electrical detonators, represented by a resistor R_1 between terminals T_1 and T_2 , an electrical current from a battery 12 first charges two series capacitors C_1 and C_2 in parallel with R_1 . During charging, current flow through the detonators is prevented by a silicon-controlled rectifier SCR_1 in series with R_1 . When the detonating circuit is fired, a gate signal permits SCR_1 to conduct current, enabling C_1 and C_2 to discharge through the detonator circuit R_1 , with sufficient energy for detonating an explosion.

To produce the high voltage required for initiating detonators R_1 , battery 12, through a normally open charging switch 15 S_C is connected in series with the medium voltage inputs of a medium-to-high-voltage DC converter 14. High-voltage DC appearing at the converter output terminals is fed to capacitors C_1 and C_2 through a limiting resistor R_2 and a buffer diode D_1 . Two large resistors R_3 and R_4 , in parallel with C_1 and C_2 respectively, serve as bleeders and a voltage divider to improve capacitor charging performance.

In actual operation of detonating circuit 10, capacitors C_1 and C_2 are charged by closing charging switch S_C . Discharge, or firing, is controlled by a lockout circuit incorporated in the detonator circuit. The lockout circuit prevents firing until C_1 and C_2 are fully charged, insuring adequate firing potential for detonators R_1 , and preventing hazardous misfires. Indirectly, through a timing circuit, a unijunction transistor Q_1 in the lockout circuit controls the gate signal to SCR_1 . Four zener diodes Z_1-Z_4 in series with a neon glow lamp NE_1 are joined in parallel with series capacitors C_1 and C_2 , with one diode Z_4 between the glow lamp and the ground terminal of battery 14. Between the glow lamp and Z_4 , the emitter of unijunction transistor Q_1 is connected through a normally open firing switch S_F . When C_1 and C_2 are sufficiently charged, the neon glow lamp conducts, and voltage to trigger Q_1 appears at S_F . The neon glow lamp acts both as a lockout to prevent firing with insufficient charge on the capacitors, and as a visual indicator that the circuit is ready to trigger.

Driving potential for transistor Q_1 is derived from a low-voltage terminal V_L between a resistor R_5 and a zener diode Z_5 in series with battery 12 and switch S_C . The zener diode regulates the potential between V_L and the battery ground to a stable level suitable for unijunction operation. Because switch S_C must be closed to produce an output at V_L , triggering of the unijunction is prevented unless charging potential appears across capacitors C_1 and C_2 . This construction operates as an additional safeguard against misfiring of the detonator circuit.

To fire the detonator circuit, switch S_C is first closed until lamp NE_1 glows, indicating that firing potential has been reached across C_1 and C_2 . Firing switch S_F is then closed to trigger transistor Q_1 and ultimately gate SCR_1 . With low-voltage terminal V_L connected to one base lead, triggering of Q_1 causes a signal to appear at the other base lead 16 and at an output terminal T_3 . A resistor R_6 in parallel with a capacitor C_3 carries this signal to ground and provides a time constant sufficient to prevent firing by spurious signals appearing at terminal T_3 . From terminal T_3 the firing signal is fed to a timing circuit for controlling the gate signal input to SCR_1 to regulate buildup and reduction of power consumption in R_1 .

U.S. Bureau of Mines Schedule 16E requires that the voltage across terminals T_1 and T_2 of the electrical blasting machine be reduced to a level precluding accidental post firing ignition within 15 milliseconds after initial detonating contact is made. Initial detonating contact occurs when, at a time t_0 , SCR_1 receives a gating pulse from the timing circuit through a terminal T_4 . In response to the gate pulse, SCR_1 conducts, discharging capacitors C_1 and C_2 through R_1 . Within 15 milliseconds after initiating the discharge, all voltage between terminals T_1 and T_2 must be removed. For this purpose a small primary shunt resistor R_7 , in parallel with R_1 , and also with C_1 and C_2 , is used to provide a short time constant for discharging the capacitors.

Shortly after gating pulse t_0 reaches SCR₁, a second gating pulse t_1 is transmitted from the timing circuit, through a terminal T₅, to a second silicon-controlled rectifier SCR₂ which completes the primary shunt circuit in series with R₇. After detonators R₁ have fired, the gating pulse t_1 opens SCR₂ to rapidly dissipate through R₇ any charge remaining across C₁ and C₂. A diode D₂ across terminals T₁ and T₂ provides a circuit path for dissipating any residual inductive or capacitive potential remaining across T₁ and T₂. Within a short time the entire charge on capacitors C₁ and C₂ is safely dissipated.

Safe operation of the electrical blasting machine requires that the potential across capacitors C₁ and C₂ be dissipated without fail shortly after initiating capacitor discharge. With R₇ and SCR₂ as the only shunt path available for this purpose, any defect in these elements has potentially catastrophic consequences. To preclude this result, a secondary shunt path, including a resistor R₈ in series with a silicon-controlled rectifier SCR₃, is provided in parallel with R₇ and SCR₁ to act as a backup. Shortly after gating pulse t_1 reaches SCR₂ to shunt current through R₇, a third gating pulse t_2 passes from the timing circuit, through a terminal T₆, to gate SCR₃. Under normal conditions, little or no current flows through this path. But if the primary shunt circuit fails to operate, the secondary circuit reduces the voltage across terminals T₁ and T₂ within the required 15 millisecond period. To disable the charging circuit if the primary shunt fails to operate, a fuse F₁ is connected between the primary and secondary shunts. If the primary shunt fails, dissipation of the capacitor charge in R₈ causes sufficient current flow to blow F₁, preventing capacitor recharge until the defect is corrected. In parallel with the fuse, a neon glow lamp NE₂, in series with a large resistor R₉, illuminates after the fuse blows to indicate the defective condition.

A timing circuit suitable for supplying to the detonator circuit the three precisely spaced signals t_0-t_2 is shown in FIG. 2. At the left side of the timing circuit the firing signal from the unijunction transistor Q₁ in the lockout circuit shown in FIG. 1 is input at terminal T₃. From T₃ the firing signal passes simultaneously to three independent time delay generators 18-22. Timing is generated by integrated circuit (IC) logic chips which respond to the trigger signal from the unijunction. From terminal T₃ the trigger signal travels through a conductor 24 to generator 18, where it is input to a logic chip IC₁. Upon receiving the signal, the logic chip initiates charging of a capacitor C₄ in series between IC₁ and a resistor R₁₀. The free end of R₁₀ is joined to low-voltage terminal V_L, derived from FIG. 1, to bias a second logic chip IC₂, connected by a conductor 26 between C₄ and R₁₀. When the voltage across C₄ overcomes the bias, the voltage input at conductor 26 is transmitted by IC₂ to a conductor 28. From output conductor 28 this voltage is fed forward to an integrated circuit amplifier IC₃, and back to IC₁ through a conductor 30. At IC₁, the signal resets the timing generator. Amplifier IC₃ provides isolation and signal gain, delivering a timing pulse t_0 , through a capacitor C₅, to an output terminal T₇.

In timing generators 20 and 22 additional logic chips are employed to provide variable time delay. To obviate unnecessary repetitious description, elements with corresponding functions in the three generators are similarly numbered. From terminal T₃ the trigger signal travels through a conductor 32 to generator 20, where it is input to a logic chip IC₄. Upon receiving the signal, the logic chip initiates charging of a capacitor C₆ in series between IC₄, a fixed resistor R₁₁, and a variable resistor R₁₂. The free end of R₁₂ is joined to low-voltage terminal V_L to bias a logic chip IC₅, with inputs connected between C₆ and R₁₁, for operation in a manner similar to IC₂ in generator 18. While the delay time of generator 18 is fixed, however, variable resistor R₁₂ enables variation of the charging time constant of C₆ so that the delay between receipt of the firing signal at IC₄ and transmission of a pulse from IC₅ through an output conductor 34 can be precisely regulated. From conductor 34 the output pulse of IC₅ is fed back through a conductor 36 to reset IC₄, and forward to an intermediate logic chip IC₆. At the output of IC₆, a capacitor C₇ in series with a grounded resistor R₁₃ receives the signal for input, 75

through a conductor 24 between C₇ and R₁₃, to a series of elements duplicating timing generator 18. Ultimately a control pulse arrives at a timing output terminal T₈ at a time t_1 shortly after the initial timing pulse t_0 . In a similar manner a third timing pulse t_2 is produced at output terminal T₉ in generator 22 shortly after pulse t_1 .

From terminals T₇-T₉ in FIG. 2 the three timing pulses are fed to an SCR drive circuit shown in FIG. 3. Because SCR₁-SCR₃, shown in FIG. 1, require a higher gate current than available at the timing circuit output, an intermediate gate drive stage 40 is required for raising each timing pulse to the required level. Three similar circuits, one for each timing pulse, are employed for this purpose. Corresponding circuit elements in each gate circuit are shown with similar reference numerals.

In gate drive stage 40 a medium driving voltage is input to a conductor 42 from a terminal V_M connected to switch S_C, as shown in FIGS. 1 and 3. Between conductor 42 and ground are connected a cutoff resistor R₁₄ and a capacitor C₈. Under steady-state conditions the voltage V_M is stored on C₈. Between R₁₄ and C₈ is connected the anode of a silicon-controlled rectifier SCR₄. When a timing pulse, t_0 for example, appears at the associated input terminal, T₇ in this case, it is fed to the gate of SCR₄ by a conductor 44. The timing pulse gates the SCR, causing current to flow from C₈ through the SCR cathode to the appropriate input terminal in the detonator circuit, terminal T₄ in the case of timing pulse t_0 . As C₈ discharges the voltage across R₁₄ rises, preventing continuous current flow through the SCR. Between the cathode of SCR₄ and the detonator input terminal the gating current passes through a decoupling capacitor C₉, and a diode D₃ which prevents feedback between the individual SCRs in the gate drive and detonator circuits. A gate holdoff resistor R₁₅ between the cathode and gate of SCR₄ provides a gate to cathode current path while preventing spontaneous gating. Gate holdoff resistors R₁₆ between the detonator circuit SCR gates and ground perform a similar function. A resistor R₁₇, passing from between C₉ and D₃ to ground, dissipates residual voltage across D₃ when the detonator gating pulse ceases. In this way the detonator gating pulses to SCR₁-SCR₃ are held to a short predictable duration.

As is apparent in the above description, our invention enables safe and efficient blasting in hazardous atmospheres. To exemplify the safety features of the invention, the basic operation will now be summarized. First, switch S_C is closed to charge energy storage capacitors C₁ and C₂. Until glow lamp NE₁ illuminates, the lockout circuit prevents discharge so that the hazards of firing with insufficient voltage are avoided. When the capacitors are fully charged NE₁ illuminates, indicating that the detonator circuit is prepared for firing, and also making voltage available at the firing switch S_F. Firing switch S_F is then closed. Then, only if charge switch S_C remains closed, unijunction Q₁ triggers, producing a firing signal at terminal T₃ and simultaneously activating timing generators 18-22. In a short time a first timing pulse t_0 is transmitted from generator terminal T₇ to gate SCR₁ in the detonator circuit and cause discharge of C₁ and C₂ through the detonators R₁. Shortly afterward, a second timing pulse t_1 gates SCR₂ to provide a primary shunt path around R₁. Then, within the 15 millisecond allowable period, a third timing pulse gates SCR₃ in the secondary shunt path around R₁. If, for some reason, the primary shunt fails to operate, current flow through the secondary shunt blows fuse F₁, disabling the detonator circuit and illuminating glow lamp NE₂ to signal the defect.

Although construction of our invention is not limited to a particular circuit, the following values of circuit elements were used effectively in the preferred embodiment:

SEMICONDUCTORS

While our invention is described as a specific preferred embodiment, with specific circuit parameters given in addition, equivalent designs and elements are expected. For this reason, the scope of the invention is limited only by the following claims:

We claim:

1. An apparatus for applying an electrical charge across a pair of terminals and for removing the charge within a short, definite duration comprising:

a capacitive discharge circuit,

means for storing an electrical charge in the capacitive discharge circuit,

a pair of terminals,

means for applying the electrical charge across the pair of terminals at a time t_0 ,

primary shunt means for applying a first low-resistance shunt across the capacitive discharge circuit at a later time t_1 , to rapidly dissipate the electrical charge,

secondary shunt means for applying a second low-resistance shunt across the capacitive discharge circuit at a still later time t_2 , to rapidly dissipate any remaining electrical charge.

2. An apparatus as claimed in claim 1, further comprising: means for preventing the application of the charge across the pair of terminals until a specific quantity of charge is stored in the capacitive discharge circuit.

3. An apparatus as claimed in claim 1, further comprising: means for preventing storage of charge in the capacitive discharge circuit after a predetermined value of current flows in the secondary shunt means.

4. An apparatus as claimed in claim 2, further comprising: means for preventing storage of charge in the capacitive discharge circuit after a predetermined value of current flows in the secondary shunt means.

5. An apparatus as claimed in claim 1 in which:

the means for applying includes a semiconductor switch, a first timing generator actuated by the semiconductor switch, and a first silicon-controlled rectifier in series with the pair of terminals and gated by the first timing generator,

the primary shunt means includes a second timing generator activated by the semiconductor switch, and a second silicon-controlled rectifier in series with the first low-resistance shunt and gated by the second timing generator, and

the secondary shunt means includes a third timing generator actuated by the semiconductor switch, and a third silicon-controlled rectifier in series with the second low-resistance shunt and gated by the third timing generator.

6. An apparatus as claimed in claim 2 in which:

the means for applying includes a semiconductor switch, a first timing generator actuated by the semiconductor switch, and a first silicon-controlled rectifier in series with the pair of terminals and gated by the first timing generator,

the primary shunt means includes a second timing generator actuated by the semiconductor switch, and a second silicon-controlled rectifier in series with the first low-resistance shunt and gated by the second timing generator,

the secondary shunt means includes a third timing generator actuated by the semiconductor switch, and a third silicon-controlled rectifier in series with the second low-resistance shunt and gated by the third timing generator,

30 the means for preventing the application of the charge includes means for regulating a trigger voltage available for actuating the semiconductor switch in proportion to the amount of charge stored in the capacitive discharge circuit.

7. An apparatus as claimed in claim 3 in which:

the means for applying includes a semiconductor switch, a first timing generator actuated by the semiconductor switch, and a first silicon-controlled rectifier in series with a pair of terminals and gated by the first timing generator,

the primary shunt means includes a second timing generator actuated by the semiconductor switch, and a second silicon-controlled rectifier in series with the first low-resistance shunt and gated by the second timing generator,

the secondary shunt means includes a third timing generator actuated by the semiconductor switch, and a third silicon-controlled rectifier in series with the second low-resistance shunt and gated by the third timing generator,

50 the means for preventing the application of the charge includes means for regulating a trigger voltage available for actuating the semiconductor switch in proportion to the amount of charge stored in the capacitive discharge circuit, and

the means for preventing storage of charge includes a circuit interrupter connected between the means for storing charges on the capacitive discharge circuit and the secondary shunt means on one side, and the means for applying and the primary shunt means on the other side, in such a manner that all charge stored in the capacitive discharge circuit and all charge dissipated in the secondary shunt means passes through the circuit interrupter.

8. An apparatus as claimed in claim 4 in which:

the means for applying includes a semiconductor switch, a first timing generator actuated by the semiconductor switch, and a first silicon-controlled rectifier in series with a pair of terminals and gated by the first timing generator,

the primary shunt means includes a second timing generator actuated by the semiconductor switch, and a second silicon-controlled rectifier in series with the first low-resistance shunt and gated by the second timing generator,

60 the secondary shunt means includes a third timing generator actuated by the semiconductor switch, and a third silicon-controlled rectifier in series with the second low-resistance shunt and gated by the third timing generator,

the means for preventing the application of the charge includes means for regulating a trigger voltage available for actuating the semiconductor switch in proportion to the amount of charge stored in the capacitive discharge circuit, and
the means for preventing storage of charge includes a circuit interrupter connected between the means for storing

charge on the capacitive discharge circuit and the secondary shunt means on one side, and the means for applying and the primary shunt means on the other side, in such a manner that all charge stored in the capacitive discharge circuit and all charge dissipated in the secondary shunt means passes through the circuit interrupter.
